UNITED STATES PATENT OFFICE.

STEVEN HORVATH, OF BAXTER, WEST VIRGINIA.

DESIGN FOR A DRINKING-CUP.

42,326.

Specification for Design.

Patented Mar. 19, 1912.

Application filed December 9, 1911. Serial No. 664,879. Term of patent 3½ years.

To all whom it may concern:

Be it known that I, STEVEN HORVATH, a subject of the King of Hungary, residing at Baxter, in the county of Marion and State of West Virginia, have invented a certain new, original, and ornamental Design for a Drinking-Cup, of which the following is the specification, reference being had to the accompanying drawing, forming a part thereof.

The figure is a perspective view of the drinking cup, illustrating my new design.

I claim:

The ornamental design for a drinking cup, as shown.

STEVEN HORVATH.

Witnesses:

JOHN S. JACKSON,
YAL ELSAKY.
